United States Patent Office.

JOHN H. BELLAMY, OF CHARLESTOWN, MASSACHUSETTS.

Design No. 4,694, dated March 7, 1871.

DESIGN FOR A PICTURE-FRAME.

The Schedule referred to in these Letters Patent and making part of the same.

To all whom it may concern:

Be it known that I, JOHN H. BELLAMY, of the city of Charlestown, in the county of Middlesex and State of Massachusetts, have originated and designed a new and useful Pattern for a Picture-Frame, of which the following is a full, clear, and exact description, reference being had to the accompanying photographs and to the letters marked thereon making a part of this specification.

The nature of my invention consists in so combining emblems as to, above the space A, balls B, with cross-cannons C C, sword D, the whole being surmounted by an eagle, E.

On the right of space A is an anchor, F, together with a flag, G.

On the left of space A is a bugle, H, together with a flag, I.

Below space A is a five-pointed star, J, on the right of which are cross-guns K K, and on the left of star cross-sabers L L, the whole being supported by ornamental scroll-work.

What I claim as my invention, and desire to secure by Letters Patent, is—

The design for a frame, as herein set forth and described.

JOHN H. BELLAMY.
